(57) **CLAIM**

The ornamental design for an icon for a portion of a display screen, as shown and described.

DESCRIPTION

The file of this patent contains a drawing executed in color. Copies of this patent with color drawing will be provided by the Office upon request and payment of the necessary fee.

The FIGURE is a front view showing a color icon for a portion of a display screen according to our new design.

The broken line showing of a portion of a display screen forms no part of the claimed design.
